(57) CLAIM

I claim the ornamental design for a curio/china cabinet, as shown and described.

DESCRIPTION

FIG. 1 is a perspective view of my curio/china cabinet;
 FIG. 2 is a front view thereof; and,
 FIG. 3 is a right side view of my curio/china cabinet, the left side (not shown) is a mirror image thereof.
 The broken lines are for environmental purposes only and form no part of the claimed design.
